UNITED STATES PATENT OFFICE.

WILLIAM H. MEYER, OF ST. LOUIS, MISSOURI, ASSIGNOR, BY MESNE ASSIGNMENTS,
TO THE DAVIS SEWING MACHINE COMPANY, A CORPORATION OF DELAWARE.

CLOTHES WRINGER.

1,418,821.

Specification of Letters Patent. Patented June 6, 1922.

Application filed February 7, 1920, Serial No. 357,053. Renewed December 14, 1921. Serial No. 522,442.

To all whom it may concern:

Be it known that I, WILLIAM HENRY MEYER, a citizen of the United States of America, a resident of the city of St. Louis, 5 in the State of Missouri, have invented certain new and useful Improvements in Clothes Wringers, of which the following is a full, clear, and exact description, reference being had to the accompanying drawings, 10 forming a part of this specification.

This invention relates to improvements in clothes wringers, the main object being to produce a strong and simple wringer structure provided with a simple releasing device 15 whereby the pressure at the wringer rolls may be easily and quickly released.

Fig. I is a front elevation, partly in section, illustrating a wringer embodying the features of this invention.

20 Fig. II is a vertical section taken approximately on the line II—II of Fig. I.

To illustrate the invention I have shown a wringer frame comprising upright end members 1 forming housings for the bearings 2 and 2' in which the wringer rolls 3 and 3' are rotatably mounted, said rolls being provided at their ends with journals engaging the bearings 2 and 2' respectively. The wringer frame also includes horizontally disposed upper members 4 integrally connected to the upright members 1.

Compression springs 5 are interposed between the upper bearings 2 and a tie-bar 6. Screws 7, acting upon end portions of the 35 tie-bar 6, may be adjusted to vary the pressure of the springs 5. These springs allow the upper roll 3 to move toward and away from the lower roll and they tend to force the upper roll into engagement with the 40 lower roll.

To illustrate the preferred form of the invention I have shown a thrust-receiving bar 8 arranged between the rigid frame members 4 and located immediately above the tie-bar 6. Nuts 9 are secured to the end portions of the thrust-receiving bar 8 to receive the adjusting screws 7. It will now be understood that the spring pressure is transmitted through the end portions of tie-bar 6 45 to the lower portions of screws 7, and thence to the nuts 9 in the thrust-receiving bar 8. If the bar 8 is held in a fixed position, the springs 5 will be retained under pressure, and the screws 7 may be adjusted to vary 50 the pressure. However, if the thrust-re-

ceiving bar 8 is released, and permitted to move vertically, the spring pressure will be immediately relieved, and the upper wringer roll 3 can then be freely moved away from the lower roll. 60

I will now describe the breakable bridge which engages the top face of the thrust-receiving bar 8 to normally retain said bar in a fixed position. This bridge preferably comprises a pair of abutment wings 10 and 10' located between the upper frame members 4 and pivotally connected to the upper margins thereof as shown at 11, said frame members 4 being slotted to receive pivot loops which extend from the wings 10 and 10', and the pivots being approximately parallel with the axes of the wringer rolls. Each wing 10 and 10' is approximately L-shaped in cross-section to provide a horizontal abutment face engaged by the thrust-receiving bar 8 and an upwardly extending flange adapted to be engaged by a releasing clip, as will be presently described. 70

The releasing clip is in the form of a releasing lever pivoted at 13 to the upturned flange of the wing 10 and provided with a tongue 14 extending over and engaging the outer face of the wing 10'. This lever has an operating handle 15 which may be depressed to release its tongue 14 from the wing 10'. 16 designates a spring tending to retain the lever in the position shown in the drawings. 75

The clip formed by the releasing lever cooperates with the wings 10 and 10' to form a transverse bridge which extends across the upper portion of the wringer frame. This bridge is normally subjected to the spring pressure which tends to throw the thrust-receiving bar 8 in an upward direction. To break the bridge, it is only necessary to depress the operating member 15 (Fig. I) thereby releasing the tongue 14 from the wing 10'. In this event, the pressure transmitted through the thrust-receiving bar 8 will cause the wings 10 and 10' to turn on their pivots, so as to release the thrust-receiving bar 8, whereupon, the bar 8 will be thrown vertically to relieve the pressure of the springs. 90

I claim:

1. In a wringer, a frame, a pair of wringer rolls, yielding means for forcing one of said rolls toward the other, a movable thrust-receiving member subjected to the pressure of 100 110

- 2 said yielding means, and a breakable bridge spanning said frame and cooperating with said movable thrust-receiving member to retain said yielding means under pressure, 5 said breakable bridge comprising wings, pivots connecting the outer margins of said wings to said frame, the axes of said pivots being approximately parallel with the axes of said rolls, and a clip detachably connecting the inner margins of said wings, said clip being pivoted to one of said wings and movable to disconnect the inner margins of said wings.
2. In a wringer, a frame, a pair of wringer rolls, yielding means for forcing one of said rolls toward the other, a movable thrust-receiving member subjected to the pressure of said yielding means, and a breakable bridge spanning said frame and cooperating with 10 said movable thrust-receiving member to retain said yielding means under pressure, said breakable bridge comprising a pair of wings, pivots connecting said wings to said frame, the axes of said pivots being approxi-

mately parallel with the axes of said rolls, 25 and a releasing clip pivoted to one of said wings and overlapping the other wing so as to detachably connect the wings.

3. In a wringer, a frame, a pair of wringer rolls, yielding means for forcing one of said rolls toward the other, a movable thrust-receiving member subjected to the pressure of said yielding means, and a breakable bridge spanning said frame and cooperating with said movable thrust-receiving member 30 to retain said yielding means under pressure, said breakable bridge comprising a pair of wings, pivots whereby the outer margins of said wings are attached to said frame, the axes of said pivots being approximately parallel with the axes of said rolls, said wings having upturned flanges facing each other, and a clip comprising a lever pivoted to one 35 of said flanges and overlapping the other flange. 40

In testimony that I claim the foregoing I hereunto affix my signature,

WILLIAM H. MEYER.
